UNITED STATES PATENT OFFICE.

CURT SCHIMMELBUSCH, OF BERLIN, GERMANY.

MASK FOR CHLOROFORMING.

SPECIFICATION forming part of Letters Patent No. 429,287, dated June 3, 1890.

Application filed October 18, 1889. Serial No. 327,483. (No model.)

To all whom it may concern:

Be it known that I, CURT SCHIMMELBUSCH, medical doctor, of Berlin, in the Kingdom of Prussia and German Empire, have invented 5 a new and useful Mask for Chloroforming, of which the following is a specification, reference being had therein to the accompanying drawings.

This invention relates to a mask for chloro- 10 forming.

In the annexed drawings, Figure 1 is a plan of the mask according to this invention. Fig. 2 is a side view of the mask with the clamp raised.

Up to the present time the usual chloroform-masks have consisted of a wire frame over which there was stretched a material pervious to the air. The repeated use of one and the same covering for several patients is undesirable in view of cleanliness and contagion 20 of disease. Washing and the long-continued use with chloroform, in consequence of the shrinking of the material, diminish its perviousness to the air, which is a serious matter, since the patient with safety to his life may only inhale chloroform mixed with air. To supply for every separate case a new specially-made covering is very expensive, and the medical man is therefore in the difficulty 25 of either disregarding the question of expense or considering the risks of the repeated use to which I have just referred.

The present invention purposes, in the first place, to effect the renewal of the covering material cheaply, simply, and with expedition. This is done by placing the material 35 on the wire frame-work and by fixing it down at the edges or rim by means of an overlapping loop or clamp, and then cutting off with a pair of scissors the superfluous material.

A material advantage arises from the use of my device, as any kind of material which

is pervious to the air may be used without requiring any special preparation.

The mask consists of an oval grooved ring 45 A, adapted to the shape of the face, rounded on its inner side and made of metal, and is supplied at the one side with a hinge B, and on the other side with a convenient handle C. At the inner side of the ring A there are 50 two wires a and b, bent in the axes of the oval. A suitable loop or clamp D is hinged at B to the grooved ring A, and is fastened with a clasp arrangement on the opposite side to the hinge. 55

The mode of proceeding, when using the said mask, is to turn up the loop or clamp D, to lay the pervious material over the wires a and b, and to fix it by shutting down the loop or clamp to the grooves of the ring A. The 60 material overlapping the ring is then cut off with a pair of scissors.

What I claim, and desire to secure by Letters Patent of the United States, is—

1. A mask for administering chloroform, 65 consisting of a grooved ring curved on the inner side and provided with wires arching from one side to the other, upon which a material admitting the passage of air is laid and held by means of a loop or clamp, substan- 70 tially as described.

2. A mask for administering chloroform, 75 consisting of an open frame or ring forming the base, a movable clamp adapted to be secured to said base, and an interposed sheet of material pervious to the air, substantially as described.

In witness whereof I have hereunto set my hand in presence of two witnesses.

CURT SCHIMMELBUSCH.
